UNITED STATES PATENT OFFICE

GEROME TRUPIANO, OF BROOKLYN, NEW YORK

SAFETY CLOTHESPIN

Application filed October 4, 1930. Serial No. 486,324.

This invention relates to clothes pins.

One object of the invention is to provide a clothes pin of improved strain take up construction to prevent splitting thereof.

- 5 3 Another object of the invention is the provision of a clothes pin having improved means for engaging with an article of clothing, or the like, and with the line supporting the same.
- 10 10 Another object of the invention is to furnish a clothes pin of improved, simplified construction, and which may be made of one piece of wood, and is rugged, reliable, and efficient in use.

- 15 15 Other objects and advantages of the invention will become apparent as the specification proceeds.

With the aforesaid objects in view, the invention consists in the novel combinations 20 and arrangements of parts hereinafter described in their preferred embodiments, pointed out in the subjoined claims, and illustrated on the annexed drawings, wherein like parts are designated by the same reference characters throughout the several views.

In the drawings:

- Figure 1 is a view in vertical elevation of a clothes pin embodying the invention.
- 30 30 Fig. 2 is a similar view thereof taken at an angle to the first view.

Fig. 3 is a top plan view.

The advantages of the invention as here outlined are best realized when all of its 35 features and instrumentalities are combined in one and the same structure, but, useful devices may be produced embodying less than the whole.

- 40 It will be obvious to those skilled in the art to which this invention appertains, that the same may be incorporated in several different constructions. The accompanying drawings, therefore, are submitted merely as showing the preferred exemplification of the 45 invention.

Referring in detail to the drawings, 10 denotes a clothes pin embodying the invention. The same may preferably be of one piece construction, and may be made of any 50 suitable material that can be used for the

purpose, for instance, wood of a suitable degree of hardness, and having the grain thereof running lengthwise of the clothes pin. It can be made of any suitable or square shape.

55 The clothes pin may be provided with a head 11, or the like, at one end thereof, and extending from the other end is a longitudinal central opening or slot 12 of suitable length providing a fork with prongs 13 having flat inner sides. The ends of the prongs may be rounded at 14, and at some point along the slot 12 are provided a plurality of registering recesses 15 in said prongs. The recesses may be in relative proximity to but 60 in spaced relation with the crotch 16 of the slot.

65 Extending through the clothes pin from the head end of the same and through the handle portion 11a thereof is a compression slot 17, the plane of which is alined with that of the slot 12. The said compression slot terminates in spaced relation to the adjacent end of the slot 12, and is of lesser width than the latter. Thus a connecting 70 neck 18 is provided. The sides of the slots are out of alinement to minimize the possibility of a split along the grain, and are between the extended planes 19 of the sides of the slot 12.

75 In applying the clothes pin in the usual manner, the recessed portions 15 engage an article of clothing or the like at the rope or other supporting line. In so doing, the prongs 13 are flexed apart, while the head 80 end of the clothes pin is subjected to compression, according to the well known principles of beam constructions. The slot 17 provides a clearance for taking up such compression to prevent a crack from beginning 85 at the crotch portion 16, which is subjected to tension.

90 The position of the recesses 15 and the length of the neck 18 are proportioned so that the clothes pin may have the requisite degree of strength. Furthermore, the recesses 15 predetermine the point of application of stress with respect to the portion 18.

95 It will be appreciated that various changes and modifications may be made in the device 100

as shown in the drawings, and that the same is submitted in an illustrative and not in a limiting sense, the scope of the invention being defined in the following claims.

5 I claim:

1. A clothes pin consisting of a one piece bar member having a slot providing a fork, a handle portion at an end of the bar member, and an open ended slot alined with the first mentioned slot and spaced therefrom to provide a connecting neck portion between the slots, the slot in the handle portion being narrower than the first mentioned slot and taking up compression created in the handle portion on springing the prongs of the fork apart.
- 10 2. A clothes pin consisting of a one piece bar member having a slot providing a fork, a handle portion at an end of the bar member, and an open ended slot alined with the first mentioned slot and spaced therefrom to provide a connecting neck portion between the slots, the slot in the handle portion being narrower than the first mentioned slot and taking up compression created in the handle portion on springing the prongs of the fork apart, the sides of the slot in the handle portion being within the extended planes of the sides of the first mentioned slot, the latter having opposite registering recesses in said prongs for receiving an article and supporting line, said recesses being in predetermined spaced relation to the connecting neck portion to pre-
35 determine the stress thereon.

In testimony whereof I affix my signature.
GEROME TRUPIANO.
